UNITED STATES PATENT OFFICE.

HELMER KINDSTRAND, OF ROCKFORD, ILLINOIS.

HAND-VISE AND HOLDER THEREFOR.

1,030,242.

Specification of Letters Patent. Patented June 18, 1912.

Application filed November 7, 1911. Serial No. 658,931.

To all whom it may concern:

Be it known that I, HELMER KINDSTRAND, a citizen of the United States, residing at Rockford, in the county of Winnebago and 5 State of Illinois, have invented certain new and useful Improvements in Hand-Vises and Holders Therefor, of which the following is a specification.

The present invention relates to a hand 10 vise more especially adapted for holding pins and similar work while they are being operated upon, and to a holder or support for the hand vise which will enable the hand vise to be held in rigid position while 15 the work is being operated upon and at the same time permit the hand vise to be moved out of its held position for the purpose of trying the fit of the work, without loosening the bench vise or other means which is holding 20 the hand vise in position. The holder for the hand vise is so configured that the vise may be readily turned within the holder for the purpose of presenting different sides of the work; and the holder may be said to 25 constitute a bearing for the hand vise in which it turns.

The objects of the present invention are, to provide a holder for the hand vise, which is cheap and simple of construction, and 30 which will provide a firm and rigid support for both the tool and the work; and to configure this holder or support so that different sizes of work can be accommodated and supported without any rearrangement 35 of the parts.

A further object of the invention is to provide a hand vise which is strong and durable of construction, and which will firmly grip work of a relatively large diameter.

The invention further consists in the features of construction and the combination of parts hereinafter described and claimed.

In the drawings, Figure 1 is an elevation 45 of the hand vise and the holder of the present invention, showing the holder clamped by a bench vise; Fig. 2 is a longitudinal section of the hand vise; and Fig. 3 is a perspective of the holder.

The hand vise of the present invention 50 consists of a handle 4 of any suitable shape and configuration, which has an interiorly threaded sleeve 5 mounted therein, said sleeve being held in the handle by means of a pin 6, or otherwise. The sleeve 5 extends beyond the end of the handle and

its extended portion is formed with a circumferential groove 7. The portion of the sleeve lying outside of the handle, as will be seen by referring to Fig. 2, is of increased 60 diameter from the portion inside the handle. This portion of the sleeve extending outside of the handle is, to all intents and purposes, one end, of the handle, since the sleeve and handle are secured together by 65 the pin 6 so that they are rigidly joined together.

The stem 8 is formed with a screw-threaded end 9, which meshes with the threading of the sleeve 5, and this stem projects a substantial distance beyond the sleeve 5, and has its ends configured to form a slotted head 10. Slidably mounted upon the stem 8 is a collar 11, which is formed to provide ears 12, between which are pivotally mounted arms 13; and said arms terminate in clamping heads 14. Each of the arms 13 is slotted, as at 15; and entered into the slots and into the slot in the head 10 are toggle members 16, said members being pivotally mounted in the arms 13 and pivotally mounted in the head 10. Interposed 70 between the head 10 and the collar 11 is a tension member 17 for the purpose of maintaining the collar in engagement with the 75 end of the sleeve 5, so that said collar follows said handle in its back and forth movements.

The operation of the hand vise is as follows: When the handle 4 is rotated, it advances or recedes along the screw-threaded stem 8, depending upon the direction of rotation of the handle. If a rotative movement is imparted to the handle, causing it to advance along the stem, the collar 11 is 80 moved toward the head 10 by such advancing movement of the handle. This imparts a sliding movement to the collar along the stem 8, which carries the arms 13 upward; and since the head remains stationary, such 85 upward movement of the arms will cause the toggle members 16 to swing around their pivotal center in the head 10 in a manner to bring the clamping jaws 14 toward one another. If the handle 4 is rotated in a direction to cause it to recede upon the stem 8, the spring 17 will force the collar 11 backward along the stem in accordance with the backward movement of the handle 4 and sleeve 5, and such backward movement will 90 tend to pull the arms 13 downward, causing the toggle members 16 to swing about their 95

pivotal center in the head 10 and spread the clamping jaws 14 apart.

It will be noted that by the arrangement shown, when the jaws are spread to their maximum distance, the toggle members will more nearly approach a dead center with respect to the center 10, and hence the action of the toggle members will be the firmest and strongest at this point. This is deemed to be of particular moment, since in the clamping of large sized work, it is frequently a matter of difficulty to obtain a firm and reliable grip upon the work.

As heretofore stated, this hand vise is of a type which is peculiarly adapted for the holding of an article of work such as a pin. In the manufacture of these pins, it becomes necessary: first, to obtain a firm rest for the hand vise and work, in order to properly perform the operation of shaping the work; and, secondly, it is necessary to frequently try the pin or other work being formed to determine whether or not it is of the desired shape to fit. It is not always possible to move the article into which the work is to be fitted, and, hence, of course, in order to determine the fit, it is necessary to move the pin.

When any of the old and well known appliances, of which I am aware, are used for holding the work in place, it is necessary, in order to try the fit of the work, to either loosen the bench vise or hand vise, thus requiring a frequent clamping and unclamping of the vise, which takes time and is troublesome. It is furthermore desirable, in forming a pin or like article, to turn the work from time to time, so that all sides of it can be operated upon. This, of course, is impossible where the hand vise is being held in a bench vise.

The rest for the hand vise and work which I have devised consists of a flat faced bar-like member 18, having its ends bent to provide arms 19 and 20. The arm 19 is configured to have a forked end 21 of a size to fit in the groove 7 of the handle 4, as shown in Fig. 1, forming a rigid support for the handle, but at the same time permitting the handle to revolve within its support. An engaging of the handle in this manner prevents lateral movement of the vise within the holder. The arm 20 has its upper end formed with a groove 22, in which the work clamped by the hand vise is intended to rest, giving the work a firm support, but permitting the work to revolve in its support. Thus, the arms 19 and 20 provide rests for the tool and work, whereby

the work is given a firm and rigid support during the forming operation, and whereby the vise and tool can be revolved as desired to permit different portions of the work to be acted upon. It is obvious that in the construction shown, the vise and work can be removed at will from the holder to permit the pin or other article being formed to be tried from time to time to determine as to its fit. There is preferably a slight amount of play between the handle and forked end, in order to permit of a slight tilting of the tool, which is necessary when work of large diameter is held.

I claim:

1. In a device of the class described, the combination of a hand vise, and a holder for said vise, comprising upwardly extending end portions and an intermediate body portion, said intermediate portion being adapted to be clamped in a bench vise, the extremities of said end portions being configured, said vise having a portion thereof configured in correspondence to the configuration of the extremity of one of said end portions, the extremity of the other end portion being configured to engage the work held by the hand vise, said configured ends forming seats for the hand vise, which permit of its free removal from its holder, and said ends extending upwardly a distance to permit the body of the hand vise to lie clear of the intermediate portion, substantially as described.

2. In a device of the class described, the combination of a hand vise, comprising a handle, jaws, an actuating mechanism for the jaws, and a holder for said vise, comprising upwardly extending end portions and an intermediate body portion, said intermediate portion being adapted to be clamped by a bench vise, the extremity of one end portion being in the form of a fork constituting a semi-circular seat, the handle of the hand vise having a circular groove adapted to receive said fork, the extremity of the other end portion being configured to engage the work held by the hand vise, said ends extending upwardly a distance to permit the hand vise to be clear of the intermediate portion, and said ends forming bearings to permit rotation of the hand vise while said holder is clamped in the bench vise, substantially as described.

HELMER KINDSTRAND.
